William Bock, of Newtown, N. Y.
Letters Patent No. 1612-dated July 8. 1862.

The schedule referred to in these Letters Patent and making part of the same.

To all whom it may concern:

Be it known that I, William Bock, of Newtown, in the County of Queens and State of New York, have invented or produced a new and original design for a Hand Fire-work, which I term the "Ladies Union Tri-colored Fire-work Fan"; and I do hereby declare that the following is a

Ales 1612

full, clear and exact description of the same, reference being had to the accompanying drawings, making a part of this specification, in which -

Figure 1. is a face view of a fire-work constructed according to my design.

Figure 2, an edge view of the same.

Similar letters of reference indicate corresponding parts

in the two Figures.

This invention relates to a new and original design for a hand fire-work for ladies use, and consists in having three paper cylinders, which contain the charges, attached to sticks which radiate from the end of a handle or holder, the cylinders being covered, one with red, another with white, and another with blue paper (or natural colors) and connected at their ends by a fuse, also covered with red, white and blue paper, all arranged, as herein-after described, to resemble a fan from which the name is derived.

In the accompanying drawings A, represents a stick which forms the handle or holder and B.B', are two branch sticks which are attached to A, in oblique positions at opposite sides of it, the end of the stick or handle A, and the two branch sticks B.B', radiating from a point on A, as a centre. C. C'. C", are three paper cylinders which are attached to the ends of the sticks A. B. B', and one C. is covered with red paper, the other C', with white paper, and the other C", with blue paper. These cylinders are charged in the ordinary way with proper combustible materials, to produce when ignited red, white and blue flames. The outer ends of the cylinders C. C'. C", are connected by a fuse D, one part a. of which is covered with red paper, and the other part b. with white, and another part c. with blue as shown in Figure 1; and the sticks B.B', at their junction with the stick A, are covered with blue paper d. The stick A, just below the blue paper d, is covered with gilt figured paper e, and the sticks B.B', and A, just below the cylinders C. C'. C", are covered with gilt figured paper f. The general appearance of the whole is that of a fan in skeleton form, as shown in Figure 1.

Having thus described my invention what I claim as new is -

3

Dec. 16/12

The general configuration of the parts in connection with the national colors, red, white and blue, disposed as shown and described, to form a new and original design for a hand fire work termed the "Ladies Union Tri colored Fire work Fan".
